Primary Examiner — W. A. Teddy Falloway

(57) **CLAIM**

We claim the ornamental design for a nesting bottle, as shown and described.

DESCRIPTION

FIG. 1 is a perspective view of a nesting bottle with the top removed from the bottom showing our new design;

FIG. 2 is a perspective view thereof;

FIG. 3 is an exploded perspective view thereof;

FIG. 4 is a bottom perspective view thereof; and,

FIG. 5 is a front view thereof.

1 Claim, 5 Drawing Sheets
